UNITED STATES PATENT OFFICE.

JOSEPH CHARLES AUGUSTE LABRÈCHE, OF EDMONTON, ALBERTA, CANADA.

CIGAR-CUTTING TOOL.

1,109,073.

Specification of Letters Patent. Patented Sept. 1, 1914.

Application filed August 13, 1913. Serial No. 784,572.

To all whom it may concern:

Be it known that I, JOSEPH CHARLES AUGUSTE LABRÈCHE, a subject of the King of Great Britain, and resident at Edmonton, in the Province of Alberta, in the Dominion of Canada, have invented certain new and useful Improvements in Cigar-Cutting Tools; and I do hereby declare that the following is a full, clear, and exact description 10 of the same.

The invention is a "cigar cutting tool" and has for its object to provide a neat, simple and compact pocket tool with which any other tools such as a pocket comb, knife 15 or the like may be readily combined.

The invention consists essentially of a pair of side plates distanced and coupled, between which is longitudinally secured a backbone spring, one end of which is formed 20 into a loop sharpened at its lower edge and adapted to coact with alined holes in said side plates. The side plates form a casing into which, if desired, a comb, knife, or the like may be hinged, in which case the spring 25 would be extended so that the opposite end from the loop forms the backbone spring for the additional tool.

The invention is shown on an enlarged scale in the accompanying drawings in 30 which:—

Figure 1 is a longitudinal section through the casing and Fig. 2 an underside edge view.

Referring to the drawings 1 and 2 are the 35 side plates forming the casing and distanced apart and coupled at one end by the block 3, rivets being passed through said block and plates. The other ends of said plates are distanced by the backbone spring 40 4 riveted at 5 to said plates so as to leave its ends free. A comb 6 is hinged at 7 between said plates at one end of the casing and folds within said casing with its teeth inward, the comb extending nearly the full 45 length of said casing in the folded position and being formed with the squared end 8 adapted to contact the end 9 of the spring 4 for snap action as in the case of an ordinary penknife, in fact I may use a knife blade 50 in place of the comb if desired. The other end of the backbone spring 4 beyond the

rivets 5 is thinned down to secure greater springiness and just beyond the outer end of the comb is curled into the loop 10 the lower edge of which is sharpened to form 55 the knife 11 adapted to work in combination with alined co-acting lateral holes 12 through the plates 1 and 2 to form a cigar cutter, which is operated by pressing the upper end of said loop into the finger depression 13 at the upper edge of the casing. Other tools may also be combined in the casing if desired, and in the drawings the lower edge of the casing is formed with the hooks 14, which, with the recesses 15, form 60 a crown stopper remover. Also said lower edge contains a cork puller 16 and a button hook 17 hinged between its side plates and working in conjunction with a backbone spring 18 in the manner of a penknife. The 70 point of the cork puller preferably comes between the hooks 14 for protection in the folded position and the inner end of the shank of the button hook may be provided with a prong 19 on the inner side forming 75 a nail cleaner. I may make the button hook thinner and hinge a knife blade alongside thereof between the plates if found desirable.

The arrangement of the cigar cutter is 80 important as it is very effective for the purpose, takes up very little space and is very simply formed by extending the backbone spring 4.

What I claim as my invention is:—

In a cigar cutting tool, a casing formed of a pair of side plates distanced and coupled and having alined coacting lateral holes to receive a cigar tip, a backbone spring secured longitudinally within said casing, 90 the outer end of said spring being formed into a loop extending partly out of the casing at its upper end and sharpened at its lower end to a knife edge adapted to form a cigar cutter in conjunction with said holes. 95

Signed at Montreal, P. Q., this 7th day of July, 1913.

JOSEPH CHARLES AUGUSTE LABRÈCHE.
